HARROW TOOTH

Filed July 29, 1932

UNITED STATES PATENT OFFICE

GEORGE KAISER, OF FOLCROFT, PENNSYLVANIA

HARROW TOOTH

Application filed July 29, 1932. Serial No. 625,961.

This invention relates to an improved harrow tooth, and the manner in which it may be mounted on and secured to a harrow tooth support or standard.

5 The invention has for its purpose to provide a tooth of this kind which is reversible so that either end of the tooth can be operated in the soil between the rows of crop, for not only breaking up the soil, but also for cutting 10 and weeding the foreign growth.

Since the harrow tooth is reversible, that is to say end for end, the tooth is therefore renewable. For example when the cutting edges of the tooth at one end thereof are 15 dulled, the tooth can be detached, and then replaced with the other end in operative position.

Another purpose is to provide a tooth of 20 this kind which is V shaped in cross section, with its opposite ends provided with converging cutting edges, into which the offset converging flanges merge, acting to ride under the surface of the soil and thereby sever the 25 roots of any foreign growth between the rows of crop.

Another purpose is to provide an improved 30 single means for mounting the tooth upon a support or standard of the harrow, the tooth being V shaped substantially throughout its length, and since it straddles the support or standard a twisting movement of the tooth is prevented.

It is to be understood that the particulars 35 herein given are in no way limitative, and that while still keeping within the scope of the invention, any desired modification of details and proportions may be made in the construction of the appliance according to circumstances.

40 The invention comprises further features and combination of parts to be hereinafter set forth, shown in the drawing and claimed.

In the drawing:—

45 Figure 1 is a view of the harrow tooth as mounted upon a standard or support of the harrow.

Figure 2 is a sectional view on line 2—2 of 50 Figure 1 showing the V shaped construction of the tooth so that it is prevented from turning.

Figure 3 is an enlarged detail view of the tooth detached from the standard.

Figure 4 is a longitudinal sectional view on line 4—4 of Figure 3.

Referring to the drawing 1 identifies a standard or support, which is adapted to be carried by any suitable harrow frame or structure (not shown), and an edge of the standard where the tooth is mounted is V shaped as shown at 2, and engaging this edge is a harrow tooth 3, which is likewise V shaped in cross section, conforming to the V shaped edge in order to prevent turning or twisting of the tooth, especially when the single fastening means is tightened. This fastening means comprises a bolt 4, the head 5 of which is peened or swaged down upon the outside diverging surfaces 6 of the tooth acting to afford a secure clinch upon the tooth. The shank 7 of the bolt immediately adjacent the head thereof is square or rectangular in cross section as shown at 8. This square or rectangular portion passes a substantial distance through the standard, for example substantially one half way through assisting materially in preventing the bolt from turning, when applying a nut 9 to the lower end of the bolt, thereby drawing the bolt tightly in position and clamping the V shaped portion of the tooth against the V shaped edge of the standard, it being obvious that the square or rectangular portion of the shank likewise passes through the apex of the V shaped portion of the tooth.

The opposite ends of the tooth are V shaped, 85 and such portions have converging cutting edges 10.

Also the opposite end portions of the tooth are flared or upset as shown at 11, and such flared or upset portions merge into the converging cutting edges. Furthermore the flared or upset portions at the opposite ends of the tooth merge into or follow over the apex of the V shaped portion of the tooth, 90 as shown at 12 at the points where the sharpened edges converge to the rounded apexes. These flared or upset portions travel under the surface of the soil and the sharpened edges act to sever the roots of foreign growth 95 between the rows of crop. Also by an adjust- 100

ment of the angle of the standard in any well known conventional manner with respect to the frame of the harrow the depth of the tooth into the soil can be regulated.

5 Obviously this construction of harrow tooth enables the tooth to be reversed and consequently renewing the tooth.

Opposite sides of the tooth substantially mid way the length have cut away portions 10 13, which permit the broken up soil to fall back upon the surface of the soil as the tooth operates.

The invention having been set forth, what is claimed is:

15 1. As an article of manufacture, a harrow tooth, comprising a body V shaped in cross section to conform to and engage a V-shaped edge of a supporting standard, with means passing through the tooth and through the 20 supporting standard to secure the tooth in place and thereby prevent its turning, the opposite end portions of the tooth having flared or upturned portions provided with cutting edges converging to rounded apexes, thereby 25 rendering the tooth reversible and consequently renewable.

2. A reversible renewable harrow tooth, comprising a body V shaped in cross section to be mounted upon a supporting standard, 30 said tooth at its opposite ends having flared or upset portions provided with cutting edges converging toward rounded apexes, the opposite sides of the tooth substantially mid way the apexes of the cutting edges being 35 provided with cut away portions to permit the broken up soil to pass and fall back upon the surface of the soil.

In testimony whereof I affix my signature.
GEORGE KAISER.
